UNITED STATES PATENT OFFICE.

MILTON S. DUNKELBERGER, OF DAYTON, OHIO.

TOY.

1,263,851.

Specification of Letters Patent. Patented Apr. 23, 1918.

Application filed January 19, 1917. Serial No. 143,405.

To all whom it may concern:

Be it known that I, MILTON S. DUNKELBERGER, a citizen of the United States, residing at Dayton, in the county of Montgomery and State of Ohio, have invented a new and useful Improvement in Toys, of which the following is a specification.

This invention relates to a new and useful improvement in toys.

10 The principal object of the invention is to provide a toy which will not only afford intense and continuous amusement for a child, but in addition will be a source of instruction to him.

15 The invention contemplates the provision of a miniature steam-shovel housing to which there is attached a swinging scoop that receives sand or other fine material at a low level, and automatically dumps it 20 when it reaches a higher elevation. The sensation of seeing the sand shoveled up and automatically dumped is a pleasing one to the child, as well as a source of mechanical instruction to him.

25 The preferred form of embodiment of my invention is illustrated in the accompanying drawings, of which Figure 1 is a side elevation of my improved toy, showing the scoop in its dumping position. Fig. 2 30 is a side elevation of the scoop, and its supporting and dumping mechanism, showing said scoop just before it releases its contents. And Fig. 3 is a perspective view of the scoop and its attachments.

35 Throughout the specification and drawings, similar reference characters denote corresponding parts.

In a detailed description of the preferred form of embodiment of my invention, the 40 numeral 1 designates a miniature housing preferably constructed of tin and pivotally supported for a horizontal circular movement on a wheel base 2.

45 Connected to, and projecting obliquely from, one end of the housing 1, is a supporting member 3 to the central portion of which is pivoted an arm 4 that carries on its outer end a scoop 5 whose sides are preferably trapezoidal. This scoop has the 50 usual open top or mouth portion, and a bottom 6 adapted to swing about a pivot 7 for a purpose now to be described.

Pivotaly connected to and embracing the sides of the scoop 5, is a yoke piece 8 to 55 the free end of which a cord or band 9 is

secured. This cord passes over a pulley 10 pivoted to one end of the supporting member 3, and thence to a windlass 11 mounted within the housing 1 and controlled by a crank 12 which is rendered accessible 60 through an opening 13 in said housing. While I have shown manual means for operating the windlass 11, any other suitable means for turning it may be employed if desired. 65

By means of the cord 9 the scoop 5 may be raised and lowered, and since it is secured to the outer end of the oscillating arm 4, the scoop when raised will be changed from its horizontal shoveling position to an upright one for unloading as follows.

Referring to Figs. 1 and 2, it will be observed that the swinging bottom 6 of the scoop 5 has an inward extension 14. This extension is normally engaged by a pawl 15 which projects downwardly from, and is mounted upon, a pivot 16 secured to the swinging arm 4 a short distance from the scoop 5. A cord or other suitable band 17, which becomes taut only under the circumstances to be hereinafter described, extends from the lower end of the pawl 15 to the supporting member 3. 70

The normal position of the pawl 15 is that shown in Fig. 2, wherein it engages the 85 extended end 14 of the bottom 6 to maintain its other end against the scoop. With its lower end thus closed, the scoop 5, when the crank 12 is turned by a child, will be drawn forwardly and upwardly by the cord 9 into 90 and above the sand pile, picking up in its travel a substantial portion of the sand and holding it intact until the operation now to be described takes place.

As the arm 4 swings about its pivot during the upward movement of the scoop, the cord 17 is gradually tightened until it draws the lower end of the pawl 15 from above the extended end 14 of the bottom 6. At this point that portion of the bottom 6 100 which supports the contents of the scoop, will drop, through gravity, to release its load of sand in a manner that will delight the child. 95

After the scoop 5 has been emptied as 105 above described, it should be permitted to descend upon the sand pile for another shoveling operation. This, the child can accomplish by turning the housing 1 upon its base 2 to bring the member 3 into such 110

a position over the pile, that the scoop 5 will descend into it when the cord 9 is permitted to unwind from the windlass 11.

As the scoop 5 descends, the outer end 5 of the arm 4 will gradually approach the member 3, thereby loosening the cord 17 sufficiently to permit the pawl 15 to fall by its own weight, above the extended end 14 of the bottom 6, which, through gravity, 10 will have assumed its closing position. Then by reversing the movement of the crank 12, the mouth of the scoop 5 will again be drawn into the sand, to carry a portion of it upward for dumping as before. 15 This operation may be repeated as long as desired by the child, for the amusement and instruction of himself as well as of those who may be in his presence.

I do not wish to be limited to the details 20 of construction and arrangement herein shown and described, and any changes or modifications may be made therein within the scope of the subjacent claims.

Having described my invention, I claim: 25 1. In a toy, the combination with a carriage, of a supporting member extending obliquely therefrom, an oscillating arm pivoted to said member, a scoop carried by said arm, means on said carriage for raising the scoop, a pivoted bottom for the latter, a device pivoted to said arm for normally locking said bottom in a closing position against said scoop, and a flexible element fixedly secured to said supporting member 30 and the locking device to withdraw the latter from the bottom of the scoop to release its contents, at a point in the upward travel of said arm.

2. In a toy, the combination with a carriage, of a supporting member extending obliquely therefrom, an oscillating arm pivoted to said member, a scoop carried by said arm, means on said carriage for raising the scoop, a pivoted bottom for the latter,

a portion of said bottom extending beyond 45 the inner end of the scoop, a pawl pivoted to said arm for engaging the extended portion of said bottom to normally maintain it in a closing position against the scoop, and a cable fixedly secured to said supporting member and the lower end of said pawl to withdraw the latter from above the extended portion of said bottom to release the contents of the scoop, after said cable is made taut by the upwardly moving arm. 55

3. In a toy, the combination with a carriage, of a supporting member extending obliquely therefrom, an oscillating arm pivoted to said member, a scoop carried by said arm, a windlass mounted on said carriage, 60 a pulley pivoted to the outer end of said supporting member, a yoke piece pivotally connected to said scoop, a raising cable for said scoop, connected to said yoke piece and extending over the pulley to said windlass, 65 a bottom pivoted to said scoop, a portion of said bottom extending beyond the latter, a pawl pivoted to said arm, the lower end of said pawl engaging the extended portion of said bottom to normally maintain it in a 70 closing position against the scoop, said pawl tapering outwardly toward its engaging end to give it sufficient weight to drop between said arm and the extended portion of the scoop bottom when the latter nears its closing position, and a cord fixedly secured to said supporting member and the engaging end of said pawl to withdraw the latter from above the extended portion of said bottom to release the contents of the scoop, 75 after said cord is made taut by the upwardly moving arm.

In testimony whereof I have hereunto set my hand this 18th day of January, 1917.

MILTON S. DUNKELBERGER.
